ROWING APPARATUS

Filed June 28, 1929

Albert E. Hecox,
By Samuel H. Davis,
Attorney

UNITED STATES PATENT OFFICE

ALBERT E. HEKOX, OF LANSING, MICHIGAN

ROWING APPARATUS

Application filed June 28, 1929. Serial No. 374,337.

This invention relates to rowing apparatus, and belongs directly to that class of devices intended to enable a person rowing a boat to move the boat in the same direction in which the rower is facing.

The object of this invention is the production of an apparatus of the nature stated which may be applied to the gunwale or edge portion of any rowboat, without the use of tools or other appliances. It is also an object of this invention to reduce the number of parts of the apparatus, and to provide those parts with reinforced portions particularly located by which the strength of the parts is believed to be materially increased in strength, enabling them to withstand any amount of rough treatment in practice. It is thought to be an obvious advantage to have such parts which are almost always given the very hardest usage, made practically unbreakable or as nearly so as may be. With this end in view the clamp base and rocker plate of this invention are reinforced as herein described.

The special construction of the parts in which this invention immediately consists is illustrated in the accompanying drawings forming a part of this application.

Fig. 1 of the drawings represents an end view of the clamp base or member of this invention which is intended to be secured to the gunwale or edge of the side of a boat shown.

Fig. 2 is a front view of the clamp base detached, and showing the front reinforced portions.

Fig. 3 is a top view of the clamp base, and shows the reinforced portions extending for a distance over and upon the top of the base.

Fig. 4 is a back view of the clamp base, and shows the reinforcing portions near the ends extending downwardly upon the back.

Fig. 5 is a bottom view of the rocker plate, showing the ears at the sides, and the crossed reinforcing ribs on the under side of the plate.

Fig. 6 is a top view of the rocker plate showing the spaced raised gear seats or supports.

Fig. 7 is an end view of the rocker plate.

Fig. 8 is a top view of all the parts assembled for operation.

Throughout the drawings and description the same number is used to refer to the same part.

Considering the drawings, the side or gunwale 1 of the boat has applied thereto a member termed herein the base clamp. It comprises a rear flat plate 2 placed against the inside of the boat, upon the top of which rests the flat top 4 of the clamp base. The base is secured by thumbscrews, such as the screw 3, and of which there are usually two alike, passing through front downwardly extending reinforced extensions or portions 5. The screw holes in the reinforces 5 are marked 6 in Fig. 2. The clamp base has the spaced up-standing ears 7, which are provided with holes 8 for pivot pins, and the lower portions of the ears are thickened into cross bars 9. It will be noted that the reinforced portion 5 at each end near the ears is extended over and upon the top 4 of the clamp base and marked 10. A reinforce portion 11 also extends down the back plate 2, as shown in Fig. 4.

The parts or members thus far mentioned and described individually may comprise integral portions of the clamp base. That is to say, the base with its ears and reinforcing extensions may be made of a single metal piece cast or otherwise formed of sufficient size and strength. The form shown is found to afford great strength for the purpose.

Figs. 5, 6 and 7 illustrate the rocker plate 12. It is usually formed for strength with the crossed ribs 13 on the under side as set out in Fig. 5. The ears 14 at the sides project downwardly as illustrated in Fig. 7. The top of the rocker plate 12 as shown in Fig. 6 is flat and it is provided at middle points near the ends with the cylindrical portions 15 termed for the purposes of this explanation gear seats. Each of the gear seats has a central hole 16 for the pivots hereafter noted.

Considering Fig. 8 it will be understood that the ears 14 of the rocker plate 12 are placed next to the ears 7 of the base clamp, and pivot pins 17 are passed through the ears of the clamp base and rocker plate to secure

the ears pivotally together. The members are shown assembled in Fig. 8. In assembling the parts the disk gears 18 and 19 are placed upon the gear seats 14. The toothed disks form each a single piece with sockets 20 and 21, of any chosen pattern, in which are fixed the customary operating handle 22 and oar staff 23. A tie plate or connection 24 extends from disk to disk and the pivot pins 25 and 26 pass through the tie plate and disks as shown.

10 The operation is as usual in such appliances. If the handle is pulled to the rower the oar sweeps in the water in like direction, and the boat is driven in the direction faced by the 15 occupant. The handle and oar may be turned inboard side by side when not in use, and the parts are not readily broken.

Having now described and explained this invention, I claim:

20 In a rowing apparatus, a clamp base having spaced up-standing ears, the said base having a flat top and a flat downwardly extending rear body plate and spaced downwardly extending reinforced portions in front provided 25 with thumbscrews for securing the clamp base to the gunwale of a boat, the said reinforced portions extending for a distance over and upon the top of said clamp base, the said rear plate having downwardly extending reinforced portions near the ends formed integrally with the said ears, a rocker plate provided on the bottom with ears arranged next to the ears of the clamp base and pivotally attached thereto, said rocker plate having di- 30agonal reinforcing ribs on the bottom, said rocker plate having on the top integral raised gear seats spaced apart, an oar and a separate operating handle having geared disks meshing with each other and pivotally secured 35 upon the said gear seats of the rocker plate.

40 In testimony whereof I affix my signature.
ALBERT E. HECOX.
